UNITED STATES PATENT OFFICE.

EUGENE R. EDSON, OF CLEVELAND, OHIO.

APPARATUS FOR SEPARATING NAPHTHA FROM OIL.

SPECIFICATION forming part of Letters Patent No. 723,849, dated March 31, 1903.

Application filed April 14, 1902. Serial No. 102,796. (No model.)

To all whom it may concern:

Be it known that I, EUGENE R. EDSON, a citizen of the United States of America, residing at Cleveland, in the county of Cuyahoga and State of Ohio, have invented certain new and useful Improvements in Apparatus for Separating Naphtha, &c., from Oil; and I hereby declare the following to be a full, clear, and exact description of the invention, such as will enable others skilled in the art to which it pertains to make and use the same:

My invention relates to improvements in apparatus for separating naphtha or other readily-volatile matter from oil, and more especially designed for separating and eliminating naphtha from oil extracted from oil-yielding material by the treatment of the said material with naphtha.

The object of this invention is to provide apparatus of the character indicated which is simple and durable in construction, which has a large capacity, which operates with facility, and whose component parts are readily assembled and as quickly and conveniently separated for repairs, renewal, and cleaning.

With this object in view and to the end of realizing other advantages hereinafter appearing the invention consists in certain features of construction and combinations of parts hereinafter described, and pointed out in the claims.

Referring to the drawings, Figure I is an end elevation, largely in central transverse section, of the tank wherein the vaporizing of the naphtha or other volatile matter takes place, and this figure shows also the heat-radiating plates and other parts contained within the said tank. Fig. II is a side elevation, largely in central section, of the said tank, and shows also parts within or connected with the tank. Fig. III is a section in detail, showing a portion of one of the heads instrumental in supporting the heat-radiating plates and illustrating more especially one of the ports formed in the said head and establishing open relation between the chambers of two adjacent plates of one of the series of heat-radiating plates. Fig. IV is a top plan in section and in detail, illustrating the formation and arrangement of the port instrumental in establishing open relation between the heating-fluid-supply pipe and the cham-

bers of the uppermost plates of both series of heat-radiating plates. Fig. V is a top plan in section and in detail, illustrating the formation and arrangement of the port instrumental in establishing open relation between the chambers of the lowermost plates of both series of heat-radiating plates and a pipe employed to conduct fluid from the said chambers. Fig. VI is a side elevation of the aforesaid tank and connected pipes. Fig. VII is a view in perspective, illustrating three heat-radiating plates and the portions of the two heads between which the said plates are interposed; and Fig. VIII is a side elevation in section, illustrating portions of the said heads and two intervening heat-radiating plates.

Referring to the drawings, *a* designates a cylindrical closed tank, which is arranged in a horizontal plane. Two vertical upright parallel or approximately parallel heads *b* and *b* are arranged within and a suitable distance apart longitudinally of the tank and preferably a short distance from opposite ends, respectively, of the chamber of the tank. The heads *b* are supported from the tank.

Two upright series of laterally and downwardly sloping heat-radiating or heating plates *c*, respectively, having a correspondingly-sloping upper imperforate side, are arranged side by side and a short distance apart laterally between the heads *b*. The two series of heating-plates *c* are arranged, therefore, in opposite sides, respectively, of the chamber of the tank. Each plate *c*, as already indicated, slopes widthwise, but is arranged longitudinally in a horizontal plane between the two heads *b* and preferably clamped at its ends by and between the said heads, as will hereinafter appear. The plates of each series of plates *c* are arranged at different elevations, respectively, and slope downwardly in opposite directions alternately, and preferably the uppermost plate of each series of plates *c* slopes downwardly and outwardly, and the lowermost plate of each series of plates *c* slopes downwardly and inwardly. Consequently each series of plates *c* comprises an even number of plates, and the arrangement of the parts is such that the uppermost plates of both series of plates *c* are arranged side by side and slope apart or diverge down-

wardly, that the lowermost plates of both series of plates are arranged side by side and slope toward each other or converge downwardly, and that the upper side of each 5 plate of each series of plates except the lowermost plate slopes downwardly toward and discharges onto the upper portion of the upper side of a plate next below. Obviously, therefore, the plates of each series of plates 10 *c* have such relative arrangement that the mixed oil and naphtha or other liquid which is to be heated within the tank *a* and which is fed or conducted to and upon the upper side of the uppermost plate of the said series 15 of plates will flow by gravity successively adown the upper sides of the remaining plates of the said series of plates.

Each plate *c* is hollow or chambered interiorly, as at *d*, and the heating fluid employed 20 in heating the said plate is conducted into the interior chamber of the said plate.

By the construction hereinbefore described it is obvious that the uppermost plates of both series of plates *c* have their upper portions near each other, and one of the heads *b* is provided, adjacent to the said upper portions of the said uppermost plates *c*, with a port *e*, which (see Figs. I, II, and IV) communicates with the chambers of the said 25 plates, and the valved pipe *f*, whose valve *g* is normally closed, discharges into the port *e* and is employed to conduct steam, hot water, or other heating fluid to the said port.

The chamber *d* of each plate of each series 30 of plates *c* except the chamber *d* of the lowermost plate of the said series of plates is placed in open relation (see Figs. I, II, III, V, VII, and VIII) with the chamber *d* of the plate *c* next below by one or more ports *h*, 35 formed in one or both of the heads *b*, and the chambers *d* of the lowermost plates of both series of plates *c* communicate with a port *k*, formed in one of the heads *b*, as shown in Figs. I, II, and IV, and a valved pipe *l* has 40 its receiving end communicating with the said port *k* and has its valve *m* normally closed. It will be observed, therefore, that upon opening the valve *g* steam or other heating fluid passes from the pipe *f* into the chamber *d* of 45 the uppermost plate of each series of plates *c* and will successively pass into the chambers *d* of the remaining plates *c* of the said series of plates, and a circulation through the chambers of the said plates will be established upon 50 opening the valve *m* as well as the valve *g*.

Fluid-tight joints are of course formed between the ends of the plates *c* and the heads *b*; but packing of joints is too well known to require description or illustration in this application. The plates *c* are, however, snugly interposed between the heads *b*, which are caused to clamp the ends of the said plates by bolts *n* and nuts *o*, which are suitably applied to hold the heads *b* and the intervening plates 60 *c* tightly together. (See Figs. I, II, VII, and VIII.) The bolts *n* extend through the heads *b* and have their heads *p* bearing against the

outer side of one of the heads *b*, and the nuts *o* are mounted upon the shanks of the bolts at and bear against the outer side of the other 70 head *b*.

The means employed for conducting the mixed oil and naphtha or other liquid into the tank *a* comprises a valved pipe *r*, whose valve 10 is normally closed. The pipe *r* (see 75 Figs. I, II, and IV) extends into the tank *a* and discharges into a funnel 12, which is arranged over and centrally between the ends of and discharges into a perforated pipe 13, which is arranged above and extends longitudinally of the upper and central portion of the upper side of a liquid-distributing plate *s*, arranged above and longitudinally of and overhanging the upper portion of the uppermost plate of each said series of plates *c*. The 80 perforations 14 of the pipe 13 are arranged to discharge onto the upper side of the plate *s*, which slopes downwardly from in under the said pipe 13 in opposite directions, so as to conduct liquid flowing from the said perforations 14 onto the uppermost plate of each series of plates *c*. Obviously, therefore, any liquid adapted to be supplied by the pipe *r* is upon opening the valve 10 of the said pipe conducted to the perforated pipe 13 and by 85 the latter discharged upon and along the distributing-plate 14 and by the said plate distributed upon the uppermost plates of both series of plates *c*. The pipe 13 is closed at its ends, as shown in Fig. II, so that liquid 90 can only escape from the said pipe through the perforations 14.

The means employed for conducting the liquid which is not vaporized within the chamber of the tank *a* outside of the said tank 105 comprises, preferably, a trough *t*, which (see Figs. I and II) is supported in any approved manner within the tank below the lowermost plates *c*. The trough *t* is closed at the ends and extends widthwise under the lower portion of the lowermost plate of each series of plates *c* and extends from end to end of the said lowermost plate, and obviously any liquid flowing or passing downwardly from the lowermost plate of each series of plates *c* 110 gravitates into the trough, and a drain-pipe 16, whose receiving end is connected with and in open relation with the said trough, extends downwardly from the trough outside of the tank and is provided with a normally closed 115 valve 17 externally of the tank. The tank *a* is provided also with a drain-pipe 18, arranged to drain from the said tank any liquid accumulating from any source upon the bottom of the chamber of the tank. 120

The tank *a* is provided (see Figs. II and VI) at the top with two vapor-outlets 20, which are arranged a suitable distance apart longitudinally of the tank, and a pipe *u*, arranged externally of the tank, is provided centrally 125 between the said outlets with two branch pipes 22, communicating with the said outlets. The pipe *u* is connected with the receiving end or inlet of a suitably-operated

pump 23. The operation of the pump 23 during the treatment of liquid within the tank *a* obviously creates suction within the said tank and facilitates the passage of vapors from the 5 tank.

The heads *b* have lateral openings 25 between the two series of plates *c* at different elevations to enlarge the means of escape from between the said series of plates of vapors arising from the liquid passing adown the downwardly and inwardly sloping plates of the said series of plates.

Sometimes it is desirable to introduce steam and air into the chamber of the tank *a* to facilitate the elimination and escape of vapors arising from the liquid heated within the tank, and consequently several valved perforated pipes *x* are arranged at different elevations, respectively, within and longitudinally of the 15 chamber of the tank *a* between the two series of plates *c* and extend outside of the tank, and are each provided externally of the tank with a normally closed valve 27, and are connected with a valved steam-supply pipe *y*, 20 whose valve 28 is normally closed, and with an air-supply pipe 30, whose valve 32 is normally closed. By the provision and arrangement of valved pipes *x*, *y*, and 30 air or steam is conducted to any pipe *x* upon opening the valve 25 27 of the said pipe *x*, according as the valve 32 of the pipe 30 or the valve 28 of the pipe *y* is opened.

A not unimportant feature is the provision of each plate *c* upon its upper side (see Figs. 35 I, VII, and VIII) with an upwardly-projecting rim or flange 33, extending along all of the edges of the said plate except along the lower edge, adown which flows any liquid conducted onto the upper side of the said plate, 40 which flange or rim extends transversely of the last-mentioned edge at the extremities of the said edge, and obviously by this construction liquid conducted onto the upper side of any plate *c* can only flow from the said plate 45 adown the aforesaid lower edge, which slopes downwardly and outwardly to the under side of the said plate, and it will be observed also that the flange or rim 33 of each plate of each series of plates *c*, except the rim or flange of 50 the uppermost plate of the said series of plates, separates the upper side of the said plate from the next plate above and positively prevents any plate from making contact with the liquid-conducting upper side of a plate 55 next below, and each plate *c*, which is arranged to discharge onto another plate *c*, preferably engages at its upper edge the flange or rim 33 of the last-mentioned and lower plate a short distance from the upper extremity of the last-mentioned plate.

What I claim is—

1. In apparatus for separating naphtha, &c., from oil, a closed tank having a vapor-outlet at the top; two upright heads arranged within 65 the tank a suitable distance apart laterally of each other; a series of plates extending between and supported from the heads at dif-

ferent elevations, respectively, which plates have their upper sides or tops imperforate and sloping laterally and downwardly widthwise of the plates; means for conducting liquid onto the upper side of the uppermost plate, and means for conducting, from the tank, the liquid flowing or passing from the upper side of the lowermost plate, and the arrangement 75 of the parts being such that each plate, except the lowermost plate, discharges onto the upper portion of the plate next below.

2. In apparatus of the character indicated, a closed tank having a vapor-outlet; two parallel or approximately parallel upright heads arranged within the tank a suitable distance apart longitudinally of the tank and a short distance from opposite ends respectively, of the tank; a series of plates arranged at different elevations respectively and extending between the said heads, which plates have their upper sides or tops imperforate and sloping laterally and downwardly widthwise of the plates; means for clamping the said heads and the interposed plates together; means for heating the said plates; means for conducting liquid onto the upper side of the uppermost plate, and means for conducting, from the tank, the liquid flowing or passing from the upper side 85 of the lowermost plate, and the arrangement of the parts being such that each plate, except the lowermost plate, discharges onto the upper portion of the upper side of a plate next below.

3. In apparatus of the character indicated, a closed tank having a vapor-outlet; two upright heads arranged within the tank a suitable distance apart laterally of each other; a series of hollow or interiorly-chambered 105 plates extending between the heads at different elevations, respectively, which plates have their upper sides or tops imperforate and sloping laterally and downwardly widthwise of the plates; means for conducting liquid onto the upper side of the uppermost plate; means for conducting, from the tank, the liquid flowing or passing from the upper side of the lowermost plate; a port formed in each head adjacent to the adjacent portions 110 of adjacent plates and in open relation with the interior chambers of the said plates; a fluid-conducting pipe communicating with the interior chamber of the uppermost plate; a fluid-conducting pipe communicating with 115 the interior chamber of the lowermost plate, and the arrangement of the parts being such that each plate, except the lowermost plate, discharges onto the upper portion of the upper side of the plate next below.

4. In apparatus of the character indicated, a closed tank having a vapor-outlet; two series of suitably-supported plates which have their upper sides or tops imperforate and sloping laterally and downwardly widthwise of 130 the plates, with the plates of each series extending longitudinally of the tank and arranged at different elevations, respectively, and with the uppermost plates of the two se-

ries of plates arranged side by side and diverging laterally and downwardly; a liquid-distributing plate arranged above and longitudinally of and overlapping and sloping 5 downwardly over the said uppermost plates; a perforated pipe arranged longitudinally of and above the said liquid-distributing plate centrally widthwise of the said plate; means for conducting liquid to the pipe; means for 10 conducting, from the tank, the liquid flowing or passing from the upper side of the lowermost plate of each series of plates; means for heating the aforesaid plates, and the arrangement of the parts being such that the upper 15 side of each plate of each series of plates, except the lowermost plate, discharges onto the upper portion of the upper side of the plate next below.

5. In apparatus of the character indicated, 20 a closed tank having a vapor-outlet; two series of suitably-supported plates which have their uppersides or tops imperforate and sloping laterally and downwardly widthwise of the plates, with the plates of each series extending longitudinally of the tank and arranged at different elevations, respectively, and with the lowermost plates of the two series of plates arranged side by side and converging laterally and downwardly; a trough 25 arranged below and longitudinally of and extending in under the adjacent portions of the said lowermost plates; means for conducting liquid from the said trough to the exterior of the tank; means for conducting liquid onto 30 the upper side of the uppermost plate of each

series of plates; means for heating the aforesaid plates, and the arrangement of the parts being such that the upper side of each plate of each series of plates, except the lowermost plate, discharges onto the upper portion of 40 the upper side of the plate next below.

6. In apparatus of the character indicated, a closed tank having a vapor-outlet; a series of plates which have their upper sides or tops imperforate and sloping laterally and downwardly widthwise of the plates, which plates are arranged within the tank at different elevations, respectively; means for heating the said plates; means for conducting liquid onto the upper side of the uppermost plate; means for conducting from the tank, the liquid flowing or passing from the upper side of the lowermost plate; perforated pipes arranged within and longitudinally of the tank at different elevations, respectively; a valved air-supply pipe and a valved steam-pipe connected and in open relation with the said perforated pipes, and the arrangement of the parts being such that each plate, except the lowermost plate, discharges onto the upper 50 portion of the upper side of the plate next below.

In testimony whereof I sign the foregoing specification, in the presence of two witnesses, this 1st day of March, 1902, at Cleveland, Ohio.

EUGENE R. EDSON.
